United States Patent

Des. 240,819
Patented Aug. 3, 1976

240,819

DESK CADDY

William Macowski, Caldwell, N.J., assignor to Katcham
& McDougall, Inc., Roseland, N.J.

Filed Mar. 6, 1975, Ser. No. 555,981

Term of patent 14 years

Int. Cl. D19—02

U.S. Cl. D19—75

FIG. 1

FIG. 2

FIG. 3

FIG. 4

FIG. 5

FIG. 1 is a perspective view of a desk caddy showing my new design;

FIG. 2 is a top plan view;

FIG. 3 is a front elevational view;

FIG. 4 is a bottom plan view;

FIG. 5 is a rear elevational view; and

FIG. 6 is a left side elevational view, the side not shown being a mirror image thereof.

I claim:

The ornamental design for a desk caddy, as shown and described.

FIG. 6
